United States Patent

Des. 235,120
Patented May 20, 1975

235,120

CHAIR

George Mergenov, Closter, N.J., assignor to Mohasco Corporation, Amsterdam, N.Y.

Filed Sept. 18, 1973, Ser. No. 398,498

Term of patent 14 years

Int. Cl. D6—01

U.S. Cl. D6—68

The figure is a perspective view of a chair illustrating my new design.

The back of the chair is conventionally plain while the side not shown is substantially identical to the side shown.

I claim:

The ornamental design for a chair, as shown and described.
